UNITED STATES PATENT OFFICE.

LIONEL J. GOTTSCHALK, OF THE UNITED STATES NAVY.

FIRE-EXTINGUISHING APPARATUS.

1,321,820.

Specification of Letters Patent. Patented Nov. 18, 1919.

Application filed December 26, 1918. Serial No. 263,294.

To all whom it may concern:

Be it known that I, LIONEL J. GOTTSCHALK, a lieutenant in the United States Navy, at present stationed at Little Rock, in the 5 county of Pulaski, State of Arkansas, have invented certain new and useful Improvements in Fire-Extinguishing Apparatus; and I do hereby declare the following to be a full, clear and exact description of the invention, such as will enable others skilled in 10 the art to which it appertains to make and use the same.

My invention relates to fire extinguishing apparatus and while it is particularly adapted for use in connection with sprinkler systems wherein fusing of a sprinkler head will automatically effect a flow and discharge of fire extinguishing liquid and gas; yet, my apparatus in its broader aspect is in no way 20 limited to such use as it can be readily employed without incorporation in a sprinkler system and its operation instituted by merely opening a valve so associated with the apparatus as to effect the initial discharge of 25 liquid from the fluid pressure tank.

More particularly my apparatus embodies a tank, capable of withstanding internal pressure, for containing one agency, preferably liquid, of a chemical extinguisher and 30 a receptacle within said tank for holding a second chemical agent, preferably an acid, together with means automatically operated under predetermined conditions to effect commingling of the two chemical agents to 35 produce a fire extinguishing liquid and gas, the latter creating pressure within the tank to discharge the contents thereof into a system of connected piping by which it is conveyed to a desired point of discharge.

The objects of the improved construction embodied in my invention are to assure positiveness and certainty of action upon fusing of a sprinkler head of an associated system or upon effecting an initial discharge of the 45 contents of the fluid pressure tank through the instrumentality of any other suitable means; to provide for rapid admixture of the chemical fire extinguishing agents immediately following the initial discharge of the 50 liquid from the pressure tank, and thereafter to maintain a retarded but continuous admixture as the discharge from the tank continues whereby an available supply of one chemical agent is held in reserve until 55 the tank is almost fully discharged so as to

render the apparatus operative after the extinguishment of one fire for the purpose of the extinguishment of a second fire, the arrangement of the apparatus being such that stopping the discharge of the tank stops the 60 automatic mixing of the chemical agents; to provide against the premature loss of the acid chemical agent through any cause by maintaining its container normally closed and effecting the opening thereof automatically upon institution of the operation of the apparatus; to provide means, when the apparatus is used in connection with a sprinkler system, to effect the initial discharge from the tank as a result of fusing of a 70 sprinkler head; and to improve and simplify the construction and operation of chemically mixing fire extinguishing apparatus generally.

I will describe my invention in the best 75 form known to me at present, but it will be understood that it is susceptible to extensive changes in parts and arrangement and to desirable additions without in any manner departing from the scope of the claims. 80

In describing my invention in detail reference will be had to the accompanying drawings wherein like characters of reference denote corresponding parts in the several views, and in which— 85

Figure 1 is a vertical longitudinal section of my invention with the parts in normal or inactive position;

Fig. 2, a similar view with the parts in the position they would occupy immediately 90 after the initial discharge from the pressure tank;

Fig. 3, a similar view showing the position of the parts when sufficient liquid has been discharged to effect complete inversion of 95 the acid container;

Fig. 4, a top view of what is shown in Fig. 1 with the tank broken away to show the interior mechanism;

Fig. 5, a section on the line 5—5 of Fig. 4; 100

Fig. 6, a perspective view of the fixed frame of the mechanism; and

Fig. 7, a perspective view of the pivotal frame of the mechanism.

Referring to the drawings A indicates a 105 pressure tank and B shows typically a sprinkler system connected to the tank by means of a siphon device in the form of an inverted U-shaped pipe C one arm 10 of which extends into the tank A and termi- 110

nates relatively near the bottom of the latter. The lower end of the arm 10 extends into a strainer 11^a suitably positioned on the bottom of the tank A. The other arm 11 5 of the pipe C is suitably connected to the sprinkler system B. The tank A is provided with an upwardly extending reduced dome extension 12 one important purpose 10 of which is to provide means for obtaining a relatively large decrease in the level of the liquid extending into the dome as the result of the discharge of a relatively small amount of liquid from the tank. Suitably fixed within the dome 12 is a frame 13 which 15 carries on its sides corresponding depending stirrups 14. Movable mounted within the frame 13 is a second frame 15, the end 16 of which normally pivotally engages a ledge 17 formed on the frame 13. Fixed to the 20 frame 15 is an acid container 18 which is normally held in upright position as shown in Fig. 1 by catches 19 engaged under the end of the frame 15 remote from the ledge 17. These catches 19 are fixed respectively 25 on shafts 20 journaled in the frame 13. Each of the shafts 20 has fixed thereto an arm 21 and these arms support a float 22 the position of which is determined by the level of the liquid in the dome 12, the normal 30 level of said liquid being such that the float will be elevated to dispose the catches 19 in holding relation to the frame 15, this normal liquid level is indicated in Fig. 1 by the line x—x. Carried by the side portions of 35 the frame 15 and positioned within the stirrups 14 respectively are pivoting studs 23 the purpose of which will presently appear. The container 18 is provided with a rupturable closure 24 preferably paraffin 40 with which is normally associated a rupturing element 25 carried by the dome 12 and designed to rupture said closure as the frame 15 and the container 18 partake of their first turning movement. Depending 45 from the frame 13 are ears 26 in which is rotatably mounted a shaft 27 having fixed thereto laterally extending parallel arms 28 which support at their free ends a float 29, the latter being disposed outside the limits 50 of the dome 12 and operable only in the major interior of the tank A. The arms 28 are provided with corresponding toothed portions 30 over which one end of the frame 15 is adapted to ride during the operation 55 of the device as will hereinafter appear. To limit unnecessary downward movement of the float 22 upon excessive decrease in level of the liquid I provide a stop 31 on the frame 13 adapted to be engaged by said float 60 when the latter swings downward a predetermined distance.

When the parts are in the position as shown in Fig. 1 with the level of the liquid in the tank at the line x—x it will be obvious 65 that a corresponding level of the

liquid will be present in the arm 10 of the pipe C. To provide for a positive and certain initial discharge from the tank upon opening one or more valves in the system B I store in the system and the arm 11 of the pipe C a quantity of liquid whose level in the arm 11 corresponds with the level of the liquid in the arm 10 and the tank A. As a result of this arrangement I quickly obtain an initial discharge from the tank upon 75 opening one or more valves in the system as a result of siphonic action as will be obvious. Assuming that this initial discharge takes place the level of the liquid in the dome 12 will sharply fall and the float 22 will descend and disengage the catches 19 from beneath the frame 15 when the latter will pivot on the ledge 17 until the pivoting studs 23 rest upon the bottom limits of stirrups 14 and the end of frame 15 adjacent to the float 22 engages the toothed portions 30 of the arms 28 where it will be held by the float 29. During this movement of the frame 15 the container 18 also moves with it causing the element 25 to 85 rupture the closure 24 and permit a quick and bountiful discharge of acid from the container. As the level of the liquid in the tank gradually decreases as a result of the pressure discharge now effected by the 90 chemical mixing, the float 29 gradually moves downward and permits further gradual turning movement of the frame 15 and container about the new pivotal center at the base of stirrups 14 and further gradual discharge of the acid in the container. During this portion of the operation an 95 available supply of acid always remains in the container so that in the event the fire is extinguished the discharge of the tank may 100 be cut off and with the remaining pressure in the tank due to gas generated the apparatus can be utilized at a subsequent time for the extinguishment of a second fire without further refilling or attention, it being 105 obvious that the shutting off of the discharge from the tank prevents further fall in the level of the liquid and thereby arrests further mixing of the chemical agents. As the frame 15 pivots on the ledge 17 the 110 studs 23 will eventually engage the bottom of the stirrups 14 and when this occurs these studs will become the effective pivot of the frame 15 and the container 18. When the level of the liquid in the tanks falls a 115 further predetermined distance the frame 15 will cease to engage the arms 28 and as a result of the location of the center of gravity of the frame 15 and tank 18 these connected elements will quickly swing to the 120 position shown in Fig. 3 to effect complete inversion of the container and complete discharge of the acid in said container.

I claim:

1. A fire extinguishing apparatus com- 130

prising a pressure tank having a fluid outlet, an acid container mounted within the tank for discharge movement, and means for automatically controlling said discharge movement during delivery of fluid from the tank.

2. A fire extinguishing apparatus comprising a fluid pressure tank having a fluid outlet, an acid container within the tank, means for effecting and arresting discharge of the contents of the container upon withdrawal and stoppage of withdrawal of fluid respectively from the tank.

3. A fire extinguishing apparatus comprising a fluid pressure tank having a fluid outlet, an acid container within the tank, means for effecting discharge of the contents of the container upon withdrawal of fluid from the tank and for arresting such discharge upon stoppage of said withdrawal.

4. A fire extinguishing apparatus comprising a pressure tank having a fluid outlet, an acid container mounted within the tank for discharge movement, and float governed means automatically controlling said discharge movement during delivery of fluid from the tank.

5. A fire extinguishing apparatus comprising a fluid pressure tank, an acid container mounted in the tank for movement from upright to inverted position and releasably held in upright position, float governed means for releasing the container, and a second float governed means for controlling the movement of the container after release.

6. A fire extinguishing apparatus comprising a fluid pressure tank having a fluid outlet, a support having successively effective pivotal connections with the tank, an acid container carried by the support, and means controlled by the fluid in the tank to first permit turning of the support on one pivotal connection and then on the other to discharge the contents of the container.

7. A fire extinguishing apparatus comprising a fluid pressure tank, a frame fixed within the tank, a support having successively effective pivotal connections with said frame, an acid container carried by the support, and means controlled by the fluid in the tank to first permit turning of the support on one pivotal connection and then on the other to discharge the contents of the container.

8. A fire extinguishing apparatus comprising a fluid pressure tank having a fluid outlet, a frame fixed within the tank, an acid container having successively effective pivotal connections with the frame, and means controlled by the fluid in the tank to permit turning of the container on one pivotal connection and then on the other to discharge the contents of the container.

65 9. A fire extinguishing apparatus com-

prising a fluid pressure tank having a fluid outlet, an acid container within the tank having successively effective pivotal supports to permit turning thereof to discharge its contents, and means controlled by the fluid in the tank to first permit turning of the container on one pivotal support and then on the other.

10. A fire extinguishing apparatus comprising a fluid pressure tank having a fluid outlet, an acid container mounted in the tank for turning movement from upright to inverted position, and means controlled by variation in the level of the fluid in the tank to permit precipitate initial and final turning movement of the container and to maintain the intermediate portion of said turning gradual.

11. A fire extinguishing apparatus comprising a fluid pressure tank having a fluid outlet, a frame pivotally supported in the tank, an acid container carried by the frame, a catch directly engaging and normally holding the frame in horizontal position, and a trip controlled by the level of the fluid in the tank for releasing the catch to permit pivotal movement of the frame.

12. A fire extinguishing apparatus comprising a fluid pressure tank having a fluid outlet, a frame pivotally supported in the tank, an acid container carried by the frame, means normally holding the frame in horizontal position, means operated by variation in the level of the fluid in the tank to release said holding means and permit precipitate initial movement of the frame, and means for retarding subsequent pivotal movement of the frame.

13. A fire extinguishing apparatus comprising a fluid pressure tank having a fluid outlet, a frame fixed within the tank and having depending stirrups, a second frame having releasable pivotal engagement with the first frame, an acid container carried by the second frame, means normally holding the second frame in position to maintain the container upright, means controlled by variation in the level of the fluid in the tank to release the holding means and permit pivotal movement of the second frame, and studs carried by the second frame engaged with the stirrups respectively by said pivotal movement to provide a connection between the frames for further relative pivotal movement therebetween.

14. A fire extinguishing apparatus comprising a liquid carrying pressure tank, a chemical agent carried in the tank and adapted to be mixed with the liquid to produce a fire extinguishing material, a pipe system for conveying the fire extinguishing material, means automatically operated by a decrease in the level of the liquid in the tank to effect discharge of the chemical agent into the liquid, and a siphon device

connecting the pipe system and the interior of the tank automatically operative upon opening the pipe system to effect initial discharge from the tank.

15. A fire extinguishing apparatus comprising a liquid carrying pressure tank, a chemical agent carried in the tank and adapted to be mixed with the liquid to produce a fire extinguishing material, a pipe system for conveying the fire extinguishing material, means automatically operated by a decrease in the level of the liquid in the tank to effect discharge of the chemical agent into the liquid, and an inverted 10 U-shaped discharge pipe having one arm extending into the tank and its other arm connected to the pipe system, said last named arm and pipe system having liquid normally stored therein whose level in said last named arm corresponds substantially to the 15 level of the liquid in the first named arm and tank whereby discharge of liquid from 20

the pipe system will effect an initial discharge from the tank.

16. A fire extinguishing apparatus comprising a liquid carrying pressure tank having a reduced dome extension whereby a relatively small discharge of liquid from the tank will produce a relatively large decrease in the level of the liquid in the dome 25 extension, a chemical container mounted in the tank for movement to discharge position, and means controlled by a decrease in the level of the liquid in the extension incident to withdrawal of liquid from the tank to 30 effect movement of the container to discharge position.

In testimony whereof I affix my signature in the presence of two witnesses.

LIONEL J. GOTTSCHALK.
